UNITED STATES PATENT OFFICE.

MICHAEL RIESNER, OF CINCINNATI, OHIO, ASSIGNOR TO WORTHINGTON PUMP AND MACHINERY CORPORATION, OF NEW YORK, N. Y., A CORPORATION OF VIRGINIA.

CYLINDER AND PLUNGER ARRANGEMENT FOR HIGH-PRESSURE COMPRESSORS.

Application filed August 19, 1926. Serial No. 130,129.

This invention relates to air compressors and more particularly to a balancing arrangement for high pressure or booster compressors.

5 In booster compressors or the last stage of multi-stage compressors for handling air or gas at very high pressures, the small diameter of the piston necessitates a compressor of the plunger type, and due to the nature of design, it must necessarily be single acting, and in the present practice of constructing such mechanisms very large frame bearing, crank and connecting rods are required, due to the extremely high peak loads, 10 and it also results in uneven torque effort.

It is an object of the present invention to provide a balancing cylinder which is not a working cylinder, in connection with such high pressure compressors, whereby the 20 frame loads will be materially decreased, thus allowing the use of a small frame and which will convert the characteristics from that of a single acting compressor to that of a two stage compressor with the resulting 25 advantages.

With these objects in view the invention consists in various features of construction and combination of parts, which will be first described in connection with the accompanying 30 drawing which shows in longitudinal section an air compressor of the preferred form embodying the invention, and features forming the invention will be specifically pointed out in the claims.

35 In the drawing is shown a high stage or booster compressor A of approved construction having associated therewith the balancing arrangement B and the operating mechanism C, which operating mechanism may be 40 of any approved type, and while a particular construction of booster or high stage compressor is illustrated, it is to be understood that the invention is applicable to such compressors irrespective of their particular 45 details of construction.

The booster or high stage compressor A comprises a cylinder 1 which has air suction or inlet through the valve structure 2 and discharge or outlet through the valve structure 3 and in operation the air, gas or other fluid under pressure is drawn into the cylinder 1 where it is compressed to a higher state of compression by action of the piston 4 after which it is discharged through the 50 discharge valve 3. In high pressure com-

pressors where very high pressures are desired the piston, because of its small diameter must be of the plunger type and is necessarily single acting because of the nature of the design of such final stage compressors. A 60 single acting compressor requires very large frame bearing, crank and connecting rods because of the extremely high peak loads and also results in uneven torque efforts. To balance the operation of the high pressure 65 compressor structure and change its characteristics from that of a single acting compressor to that of a two stage compressor, an auxiliary non-working cylinder 5 is provided in which a non-compressing piston 6 70 reciprocates. The piston 6 is connected by a flexible coupling 7 with the piston 4 of the high pressure compressor A. In the form illustrated in the drawing, the piston 6 is connected by a connecting rod 8 with the cross head structure 9 which is in turn connected to the operating shaft 10 of the operating mechanism C so that the balancing cylinder and piston structure is interposed between the piston 4 of the high pressure 75 compressor A and its operating mechanism. This construction is a matter of relationship of the parts and it is to be understood that the balancing cylinder 5 and non-compressing balancing piston 6 may be positioned at 80 any desired or convenient place relative to the piston 4 of the compressor A so long as they will properly balance the action of the compressor A and perform their functions. 85

The cylinder 5 has a port 11 communicating with its head end or the end adjacent to the high pressure piston 4 and this port 11 has connection with the atmosphere, or in multi-stage compressors with the low pressure suction so as to admit air under atmospheric pressure into the cylinder in front of the piston 6. If it is so desired the head end of the balancing cylinder 5 may be opened direct to the atmosphere through ports or openings 11' shown in dotted lines 90 in the drawing. A second port 12 communicates with the interior of the cylinder 5 back of the piston 6 at its crank end or the end adjacent to the operating mechanism C. This port 12 has connection with the cooler 95 of the first or second stage of a multi-stage compressor or may receive fluid under pressure from any suitable source. The pressure of the fluid admitted to the cylinder behind the piston 6 through the port 12 is of such 100 105 110

degree as to balance the return pressure of the piston 4 and relieve the operating mechanism of much of the stress and load normally administered thereto in single acting high pressure compressors.

The operation of the mechanism just described is as follows: Assuming that the compressor A is a booster or final stage of a multi-stage compressor, the fluid entering its cylinder 1 through the inlet 2 is under high pressure and forces the piston 4 outwardly or back with considerable force, much of which force or pressure is balanced or absorbed by the fluid under pressure within the crank end of the cylinder 5 behind the piston 6, the pressure of which is less than the pressure of fluid entering the cylinder 1 through the inlet 2. As the piston 4 returns or moves forward in its compressing stroke the pressure of the fluid in the crank end of the cylinder 5 co-operates with the power supplied through the operating mechanism C in moving the piston 4, resulting in no power loss in the operation of the compressor since the piston 6 moves against atmospheric pressure, or a pressure much lower, during the compressing stroke of the piston 4 than during the return stroke of the piston 4. The discharge from the cylinder 5 is through the same ports as the inlet thereto and the pressure remains constant within the cylinder 5 on both forward and backward strokes so that from a compressing standpoint the cylinder 5 and piston 6 are non-working or non-compressing. The opening 20 is merely a hand hole to permit access to the stuffing box 21 and also serves as a vent for the space surrounding the stuffing box but in no way affects the operation of the compressor.

It will be understood that the invention is not to be limited to the specific construction or arrangement of parts shown but that these may be modified widely within the invention defined by the claims.

What is claimed is:

1. In an air or gas compressor, the combination, with a compressing piston, of a balancing cylinder, a balancing piston therein, said cylinder receiving fluid under different pressures for non-compressing action thereon, by said balancing piston for balancing the action of said compressing piston.

2. In an air or gas compressor, the combination with a compressing piston, of a balancing cylinder, a balancing piston therein, said cylinder receiving fluid under different pressures, the fluid acted upon by the balancing piston during intake movement of the compressing piston being under higher pressure than the fluid acted upon by the balancing piston during the compressing stroke of the compressing piston.

3. In an air or gas compressor, the combination, with a compressing piston, of a bal-

ancing cylinder, a balancing piston therein, said cylinder receiving fluid under different pressures on opposite sides of said balancing piston for balancing the action of said compressing piston.

4. In an air or gas compressor, the combination, with a compressing piston, of a balancing cylinder, a balancing piston therein, said cylinder receiving fluid under different pressures on opposite sides of said balancing piston for balancing the action of said compressing piston, said balancing piston discharging fluid at its inlet pressure whereby the pressures in the balancing cylinder remain constant.

5. In an air or gas compressor, the combination with a compressing piston, of a balancing cylinder, a balancing piston therein, movable synchronously with said compressing piston, said cylinder receiving fluid at atmospheric pressure on one side of the balancing piston and fluid under pressure greater than atmospheric on the other side of the balancing piston, for balancing the action of said compressing piston.

6. In an air or gas compressor, the combination with a compressing piston, of a balancing cylinder, a balancing piston therein, movable synchronously with said compressing piston, said cylinder receiving fluid at atmospheric pressure at its head end which fluid is acted upon by the balancing piston during compressing movement of the compressing piston, and receiving fluid under pressure greater than atmospheric at its crank end which latter fluid is acted upon by the balancing piston during the intake movement of the compressing piston.

7. In an air or gas compressor, the combination with a compressing piston, of a balancing cylinder, a balancing piston therein, movable synchronously with said compressing piston, said cylinder receiving fluid at atmospheric pressure at its head end which fluid is acted upon by the balancing piston during compressing movement of the compressing piston, and receiving fluid under pressure greater than atmospheric at its crank end which latter fluid is acted upon by the balancing piston during the intake movement of the compressing piston, said balancing cylinder discharging fluid at its inlet pressure whereby the pressures in the balancing cylinder remain constant.

8. In an air or gas compressor, the combination with a compressing piston, of a balancing cylinder, a balancing piston therein, movable synchronously with said compressing piston, said cylinder receiving fluid at atmospheric pressure at its head end which fluid is acted upon by the balancing piston during compressing movement of the compressing piston, and receiving fluid under pressure greater than atmospheric at its crank end which latter fluid is acted upon

- by the balancing piston during the intake movement of the compressing piston, the pressure of the fluid received in the crank end of the cylinder being less than the pressure of inlet fluid acted upon by the compressing piston. 5
9. In an air or gas compressor, the combination with a compressing piston, of a balancing cylinder, a balancing piston therein movable synchronously with said compressing piston, said cylinder receiving fluid at atmospheric pressure at its head end which fluid is acted upon by the balancing piston during compressing movement of the compressing piston, and receiving fluid under pressure greater than atmospheric at its crank end which latter fluid is acted upon by the balancing piston during the intake movement of the compressing piston, the 10 pressure of the fluid received in the crank end of the cylinder being less than the pressure of inlet fluid acted upon by the compressing piston, said balancing cylinder discharging fluid at its inlet pressure whereby 15 the pressures in the balancing cylinder remain constant.
10. In an air or gas compressor, the combination of, a compressing cylinder and compressing piston, a non-compressing balancing cylinder, and a non-compressing piston 20
- therein and connected to said compressing piston, said non-compressing cylinder having a port at each end to receive and discharge a balancing fluid. 25
11. In an air or gas compressor, the combination, with a compressing piston, of a balancing cylinder, a balancing piston therein, said cylinder receiving fluid under different pressures, the fluid acted upon by the balancing piston during intake movement of the compressing piston being under higher pressure than the fluid acted upon by the balancing piston during the compressing stroke of the compressing piston, the pressure of fluid acted upon by the balancing piston during intake stroke of the compressing piston being less than the pressure of inlet fluid acted upon by the compressing piston. 30
12. In an air or gas compressor, the combination of, a compressing cylinder, a piston for compressing fluid to a high pressure, and means for balancing the operation thereof comprising a non-compressing cylinder receiving a balancing fluid under different pressures at pre-determined times and a non-compressing piston movable therein. 35

In testimony whereof I affix my signature.

MICHAEL RIESNER.
